UNITED STATES PATENT OFFICE.

ALBERT PATITZ, OF MERIDEN, CONNECTICUT, ASSIGNOR TO THE BRADLEY & HUBBARD MFG. CO., OF SAME PLACE.

DESIGN FOR A BASE FOR LAMPS.

SPECIFICATION forming part of Design No. 25,874, dated August 4, 1896.

Application filed July 2, 1896. Serial No. 597,913. Term of patent 3½ years.

To all whom it may concern:

Be it known that I, ALBERT PATITZ, of Meriden, in the county of New Haven and State of Connecticut, have invented a new Design for 5 a Base for Lamps, (Case D;) and I do hereby declare the following, when taken in connection with the accompanying drawing and the letters of reference marked thereon, to be a full, clear, and exact description of the same, 10 and which said drawing constitutes part of this specification, and represents a perspective view of a lamp-base embodying my design.

This invention relates to a design for a base 15 for lamps; and the design consists in the configuration and ornamentation as shown in the accompanying illustration and hereinafter described.

The base is dome-shaped in general outline, 20 and consists of four legs, terminating in upturned feet B. The legs are ornamented by a raised central panel C, surrounded by trans-

versely-ribbed scrolls D, connected by ornate open floriated festoons E, united above the legs, their line of junction being covered 25 by a leaf-like ornamentation, into which the scrolls of the legs merge. Resting upon the legs is a beaded band G, from which the crown rises, said crown being ornamented by raised medallions H, corresponding to the 30 panels upon the legs, and connected by a raised floral ornamentation I, corresponding in general contour to the festoons E, all as shown in the accompanying illustration.

I claim—

The design for a base for lamps as herein 35 shown and described.

In testimony whereof I have signed this specification in the presence of two subscribing witnesses.

ALBERT PATITZ.
